UNITED STATES PATENT OFFICE

142,954

DESIGN FOR A FIRE EXTINGUISHER

Edward H. Hansen, Elkhart, Ind., assignor to Elkhart Brass Manufacturing Company, Elkhart, Ind., a corporation of Indiana

Application October 25, 1944, Serial No. 115,971

Term of patent 14 years

(Cl. D16—2)

To all whom it may concern:

Be it known that I, Edward H. Hansen, a citizen of the United States, residing at Elkhart, in the county of Elkhart and State of Indiana, have invented a new, original, and ornamental Design for a Fire Extinguisher, of which the following is a specification, reference being had to the accompanying drawing forming a part thereof, in which:

The dominant portion of my design is shown in full lines.

I claim:

The ornamental design for a fire extinguisher, substantially as shown and described.

EDWARD H. HANSEN,
